CLAIM

The ornamental design for a wearable electronic device case, as shown and described.

DESCRIPTION

FIG. 1 is an isometric top view of the new design for a wearable electronic device case;

FIG. 2 is a front view of the wearable electronic device case;

FIG. 3 is a right side view of the wearable electronic device case, with the left side view being a mirror image;

FIG. 4 is a rear view of the wearable electronic device case;

FIG. 5 is a top view of the wearable electronic device case;

FIG. 6 is a bottom view of the wearable electronic device case;

FIG. 7 is an isometric top view of the new design for a wearable electronic device case with the clip unbent;

FIG. 8 is a bottom isometric view of the wearable electronic device case with the clip unbent;

FIG. 9 is a front view of the wearable electronic device case with the clip unbent;

FIG. 10 is a right side view of the wearable electronic device case, with the left side view being a mirror image with the clip unbent;

FIG. 11 is a rear view of the wearable electronic device case with the clip unbent;

FIG. 12 is a top view of the wearable electronic device case with the clip unbent; and,

FIG. 13 is a bottom view of the wearable electronic device case with the clip unbent.

The broken lines depict environment and are for illustrative purposes only and form no part of the claimed design.
